[57] CLAIM

The ornamental design for a front portion of a motor vehicle, as shown and described.

DESCRIPTION

FIG. 1 is a perspective view of a first front portion of a motor vehicle;

FIG. 2 is a front view of the first front portion;

FIG. 3 is a rear view of the motor vehicle;

FIG. 4 is a left side view of the first front portion;

FIG. 5 is a right side view of the first front portion;

FIG. 6 is a top view of the first front portion;

FIG. 7 is a perspective view of a second front portion of a motor vehicle;

FIG. 8 is a front view of the second front portion;

FIG. 9 is a rear view of the second front portion;

FIG. 10 is a left side view of the second front portion;

FIG. 11 is a right side view of the second front portion;

FIG. 12 is a top view of the second front portion;

FIG. 13 is a perspective view of a third front portion of a motor vehicle;

FIG. 14 is a front view of the third front portion;

FIG. 15 is a rear view of the third front portion;

FIG. 16 is a left side view of the third front portion;

FIG. 17 is a right side view of the third front portion; and,

FIG. 18 is a top view of the third front portion.

The portion of the motor vehicle shown in broken lines is for illustrative purpose only and forms no part of the claimed design.
